UNITED STATES PATENT OFFICE.

GEORGE GOULD GOING, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,243,730.

Specification of Letters Patent. Patented Oct. 23, 1917.

Application filed April 6, 1916. Serial No. 89,261.

To all whom it may concern:

Be it known that I, GEORGE GOULD GOING, a citizen of the United States, residing at Middletown, in the county of Middlesex and 5 State of Connecticut, have invented certain new and useful Improvements in Typewriting Machines, of which the following is a full, clear, and exact description, such as will enable others skilled in the art to which 10 it appertains to make and use the same.

This invention relates to typewriting machines and more particularly to associated carriage controlling and ribbon driving mechanisms.

15 One of the objects of the invention is to provide simple and practical means for disconnecting the ribbon feeding mechanism when the carriage is freed for tabulating movement.

20 Another object is to provide improved tabulating and margin releasing devices for the typewriter carriage.

A further object is to associate co-operatively, tabulating means, margin releasing 25 means, and ribbon feeding means, in a manner to insure their reliable operation and to effect advantageous results.

Other objects and advantages will be in 30 part obvious and in part noted hereinafter in connection with a description of the accompanying drawings which illustrate a typical embodiment of the invention.

The invention accordingly consists in the 35 features of construction, combinations of elements and arrangement of parts, which will be exemplified in the construction herein-after set forth, and the scope of the application of which will be indicated in the following claims.

40 In the drawings, Figure 1 is a perspective view of certain parts of a typewriter.

Fig. 2 is a side and sectional view longitudinally of the machine.

Fig. 3 is a partial top plan view thereof, 45 and

Fig. 4 is a detail view of co-operating carriage stops.

The invention is directed in general to a typewriting machine wherein spaced ribbon 50 spools carry the ribbon across the printing point of the platen and are selectively driven through a connection with the carriage return spring. Operating means is provided to free the carriage, when desired, from its 55 escapement mechanism for predetermined

adjustable tabulating movement, and the driving connection for the ribbon spools is arranged for control by the tabulator mechanism in a manner to maintain the ribbon stationary during tabulating carriage movement, whereby the printing surface of the ribbon is utilized economically. The invention is illustrated as incorporated in a noiseless typewriter. It is to be understood, however, that certain features of the invention 60 are susceptible of application as well with the same functional advantage to various other styles of machines.

Referring more particularly to the drawings, there is indicated in Fig. 1 a typewriter 70 having side walls 1 and a rear cross brace 2. A carriage 3 (Fig. 2) is mounted at the upper rear part of the machine for longitudinal letter-space and vertical case-shifting movement on a guide rail 4. A longitudinal 75 carriage rack 5 is arranged beneath the rail 4 and normally meshes with a rotatable pinion 6 having suitably splined to the lower end of its shaft an escapement wheel 7 arranged for co-operation with fixed and movable dogs of escapement rocker 8, the latter being in turn controlled by suitable universal bar mechanism and other devices, as desired, to effect letter spacing.

Two ribbon spools are mounted adjacent 85 the side walls of the machine frame and arranged to carry an inking ribbon from one to the other in the path of travel of the type carriers. The ribbon spools are provided with shafts 9 having bevel gears 10 fixed at 90 their lower ends for alternate connection with bevel gears 11 fixed on a transversely extending and longitudinally movable driving shaft 12 journaled in the side walls 1. The driving shaft 12 is in turn operated 95 through a gear connection 13 by the shaft 14 of the carriage-driving spring drum 15 so that as the carriage is fed in its letter space movement, winding motion is imparted to one of the ribbon spools. Automatic reversing means is provided to insure rewinding of the ribbon upon either spool when the same becomes unwound therefrom. For this purpose the driving shaft 12 may be provided with two fixed peaked cams 16 po- 100 sitioned beneath the lower extremities of spindles 17 vertically movable in the ribbon shafts and normally held elevated by levers 18, which are drawn toward the ribbon shafts when the ribbon is coiled about its 110

105

cores. As either spindle 17 drops when the ribbon is unwound, its lower end rides over the inclined face of one of the cams 16 and forces the driving shaft 12 longitudinally to disengage the opposite gears and connect the adjacent gears. Resilient means, such as a leaf spring 19 engaging a cone cam 20 on the driving shaft 12, may be provided to hold the driving shaft in either extreme position.

On the rear of the traveling carriage 3, and behind the platen roll, there is provided a stop rail 21 having mounted thereon a plurality of margin stops 22 and a plurality of intermediate tabulating stops 23. The stop rail is notched and the various stops are removably mounted thereon, whereby their longitudinal position with respect to the carriage may be varied. The rear of the machine is also provided with a tie brace 24 extending upwardly behind the carriage and having at its extremity spaced portions 25 between which is disposed the extremity 26 of a movable stop lever 27. This lever is extended downward and pivoted about a vertical axis 28 on a block 29, in turn mounted on a bent shaft 30 as a horizontal axis, so that the extremity 26 of the stop lever is capable of movement in the general direction of the carriage travel and also at right angles thereto. The stop lever is normally positioned in the path of movement of the margin stops 22 in such a manner that as the carriage travels to the right or left, its limit is established in accordance with the adjusted position of the margin stops. The tabulating stops 23 project from the stop rail 21 to a lesser extent than the margin stops, to thereby clear the stop lever 27.

To release the carriage at either margin for limited additional travel in the same direction, there is provided a margin release lever 31 pivoted medially to a stud 32 on the side wall of the machine and having its rear end forked at 33 to straddle the bent extremity 34 of the shaft 30. This connection is such that the shaft 30 is rotated to carry the stop lever 27 rearward and free the corresponding margin stop 22, when the lever 31 is depressed.

Tabulating mechanism is provided to simultaneously free the carriage from the escapement mechanism and to move the stop lever 27 forward into the path of movement of the tabulating stops 23 on the rail 21. More specifically, a tabulating lever 35 is pivoted at 36 to a supporting bracket 37 rigidly fixed to a front cross piece 38 of the machine frame and has at its rear extremity spaced bent ears 39, 39' straddling the adjacent portion of the margin release lever 31. The tabulating lever further has a right-angled downward extending arm 40 having pivotal connection with a rearward horizontally extending thrust link 41 con-

nected in turn at its rear end to an arm 42 fixed to a rotatable shaft 43. This shaft carries at its opposite end a depending arm 44 positioned immediately in the rear of an offset arm 45 of the relatively fixed escapement dog 46. This construction is such that upon depression of the tabulating key, the thrust link 41 is moved rearward, thereby rotating the shaft 43 to carry the arm 44 against the free end of the escapement dog 46, forcing the latter out of engagement with the escapement wheel, and thereby freeing the carriage for longitudinal tabulating movement. At the same time the lower ear 39 on the tabulating lever 35 is raised to engage the lower edge of the margin release lever 31, thereby moving the forward end of the latter slightly upward with an attendant depression of the rear end and consequent rotation of the shaft 30 to carry the extremity of the stop lever 27 forward into the path of travel of the tabulating stops 23 on the margin rail. Movement of the carriage is therefore permitted until the adjacent tabulating stop engages the stop lever end 26. Upon release of the tabulating key, the escapement dog 46 again engages a tooth of the escapement wheel 7 and the carriage is held stationary.

It will be noted that the carriage driving spring also constitutes the source of power for feeding the ribbon from one spool to the other. With the construction of the machine as thus far described, it is apparent that the ribbon would therefore be moved while the carriage is freed for tabulating work. But as no printing is effected during such travel, it is advantageous to hold the ribbon stationary and thereby economize the printing surface of the same. For this purpose, there is provided a V-shaped cam 47 fixed on the ribbon driving shaft 12, and a bracket 48 fixed on a spindle 49 disposed adjacent and parallel to the shaft 12. This bracket 48 has a rear lever arm 50 positioned to engage and ride over one of the inclined faces of the cam 47, upon rotation of the spindle, to thereby move shaft 12 longitudinally from either extreme position to an extent which disengages said shaft from both the spool shafts 9. The dimensions of the cam 47 and cam 20 are such, however, that upon reverse rotation of spindle 49 and bracket 48, shaft 12 is again urged by springs 19 to mesh the previously disengaged gears 10, 11 for rendering the ribbon feed again effective. The bracket 48 is also provided with a bent lever arm 51 which extends transversely behind an upstanding arm 52 united to the thrust link 41 of the tabulating connection. As the tabulating key is depressed, therefore, arm 52 engages bracket arm 51, rotating spindle 49 and effecting disconnection of the ribbon spools during free tabulating travel of the carriage

in the manner described. The spindle 49 is journaled through one side wall of the machine and is provided therebeyond with an operating member 53 whereby the spindle may be manually rotated independently of the tabulating mechanism when desired, e. g. for stenciling purposes.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent, is:

1. In a typewriting machine, in combination, a carriage, margin and tabulating stops carried thereby, a movable stop normally positioned to coöperate with said margin stops, means including a margin release lever for freeing said movable stop from said margin stops, ribbon feeding means, common driving means for said carriage and said feeding means, and tabulating means to free said carriage coöperable with said margin release lever to move said movable stop to contact with said tabulating stops and with said feeding means to render the latter ineffective during tabulating travel of said carriage.

2. In a typewriting machine, in combination, a carriage, spaced ribbon shafts, a driving shaft movable longitudinally for connection with either of said ribbon shafts or disconnection from both, common driving means for said carriage and said driving shaft, means including a rotatable member to effect disconnection of said driving shaft from both of said ribbon shafts, an operating handle at the side of the machine for said member, tabulating means for said carriage including a lever operable from the key-board of the machine, and a lost-motion connection between said lever and said member for permitting rotation of the latter either by said handle or by said tabulating means.

3. In a typewriting machine, in combination, a carriage, spaced ribbon shafts, a driving shaft movable longitudinally for connection with either of said ribbon shafts or disconnection from both, common driving means for said carriage and said driving shaft, automatic means to effect disconnection of said driving shaft from one of said ribbon shafts and connection with the other for reversing the ribbon feed, manually operable means to effect movement of said driving shaft from either extreme position to the other at will, independent manually operable means to effect movement of said

driving shaft from either extreme position to a central position, and independent means to effect movement of said driving shaft from either extreme position toward but not to central position.

4. In a typewriting machine, in combination, a carriage, spaced ribbon shafts, a driving shaft movable longitudinally for connection with either of said ribbon shafts or disconnection from both, common driving means for said carriage and said driving shaft, automatic means to effect disconnection of said driving shaft from one of said ribbon shafts and connection with the other for reversing the ribbon feed, manually operable means to effect movement of said driving shaft from either extreme position to the other at will, independent manually operable means to effect movement of said driving shaft from either extreme position to a central position, and resilient means to insure connection of said driving shaft with one of said ribbon shafts after operation of said automatic means, said manually operable means or said independent means.

5. In a typewriting machine, in combination, spaced ribbon shafts, a longitudinally movable driving shaft adapted for selective connection therewith, a V-shaped cam fixed to said driving shaft, and a pivoted member rotatable to ride over an inclined face of said cam for freeing said driving shaft from both of said ribbon shafts when said member is seated in the trough of said cam.

6. In a typewriting machine, in combination, vertical ribbon shafts, a horizontal driving shaft therefor adapted for selective connection therewith, a rotatable spindle extending adjacent and parallel to said driving shaft, and coöperative means on said spindle and said shaft for freeing the latter from both of said ribbon shafts.

7. In a typewriting machine, in combination, spaced vertical ribbon shafts, a horizontal driving shaft therefor adapted for selective connection with the lower ends of said ribbon shafts, a rotatable spindle extending adjacent and parallel to said driving shaft, and coöperative means on said spindle and said shaft for centering the latter to free both of said ribbon shafts.

8. In a typewriting machine, in combination, spaced vertical ribbon shafts, a horizontal driving shaft therefor adapted for selective connection with the lower ends thereof, a rotatable spindle extending adjacent and parallel to said driving shaft, and coöperative means comprising a V-shaped cam fixed to said shaft and a lever fixed to said spindle for centering said driving shaft to free both of said ribbon shafts.

9. In a typewriting machine, in combination, a carriage, ribbon feeding mechanism, common driving means therefor, means to

free said carriage for tabulating movement, and means operable by said first means to render said mechanism ineffective during tabulating movement of said carriage and 5 also operable by hand independently of said first means to render said mechanism ineffective at will.

10. In a typewriting machine, in combination, a carriage, an escapement therefor, 10 ribbon feeding mechanism including a shift- able driving part, a common driving device for said carriage and mechanism, resilient means constantly urging said shiftable part to establish ribbon drive in one or the other 15 direction, manually operable means to move said shiftable part to an intermediate position automatically maintained, and tabulat- ing means to free said carriage from said escapement and operable to move said shift- able part from either extreme position while 20 insuring its return thereto by said resilient means upon release of said tabulating means.

11. In a typewriting machine, in combination, a carriage, ribbon feeding mecha- 25 nism, common driving means therefor, tabulat- ing means including a depressible key to free said carriage for tabulating move- ment, and means operable by said tabulating means to render said mechanism ineffective 30 only during depression of said key and in- dependently operable to set said mechanism in a stable ineffective condition.

12. In a typewriting machine, in combination, a carriage, an escapement therefor, 35 ribbon feeding mechanism, coöperable stops for said carriage, a margin release key to disengage certain of said stops, a tabulator key to free said carriage from said escape- ment and to render said mechanism in- 40 effective, said tabulator key being construct- ed and arranged to act through said margin release key for insuring coöperation of certain of said stops to limit tabulating movement of said carriage, and said mar- 45 gin release key being constructed and ar- ranged to act independently of said tabu- lating key.

13. In a typewriting machine, in combi- nation, a carriage, ribbon feeding mecha- 50 nism including a shiftable part having fixed

thereon a V-shaped cam with a medial dwell, common driving means for said car- riage and said mechanism, means including a part manually operable to coact with said cam and enter said dwell for shifting said first part to a stable intermediate position wherein said mechanism is ineffective, tabulat- ing means to free said carriage for a 55 tabulating movement and constructed and arranged to cause said second part to coact with said cam without entering said dwell for shifting said first part to an intermediate but unstable position wherein said mechanism is ineffective.

14. In a typewriting machine, in combi- nation, a carriage, ribbon feeding mecha- 60 nism including a horizontally disposed and longitudinally movable driving shaft, com- mon driving means for said carriage and said mechanism, a spindle disposed parallel 65 to said shaft and fixed against longitudinal movement, coöperating means on said shaft and spindle to effect release of said mecha- nism, tabulating means to free said car- riage, and a lost motion connection between 70 said tabulating means and said spindle to insure release of said mechanism upon operation of said tabulating means.

15. In a typewriting machine, in combi- nation, a carriage, ribbon feeding mecha- 75 nism including a horizontally disposed driv- ing shaft mounted for longitudinal shifting movement to establish ribbon feed in either direction and to interrupt the ribbon feed, a common spring drive for said carriage 80 and mechanism, a rotatable but longitudinally fixed member adjacent said shaft, co- operable means on said member and shaft to move the latter to interrupt the ribbon feed, and adjacent parts on the exterior of 85 the machine to permit longitudinal move- ment of said shaft and rotation of said member.

In testimony whereof I affix my signature, in the presence of two witnesses.

GEORGE GOULD GOING.
